(57) **CLAIM**

The ornamental design for a swim vest, as shown and described.

DESCRIPTION

FIG. 1 is a front perspective view of a swim vest showing my new design;

FIG. 2 is a front view of the swim vest thereof;

FIG. 3 is a rear view the swim vest thereof;

FIG. 4 is a left side view of the swim vest thereof;

FIG. 5 is a right-side view of a swim vest thereof;

FIG. 6 is a top view of the swim vest thereof; and,

FIG. 7 is a bottom view of the swim vest thereof.

The broken lines shown illustrate partial environment of the swim vest and form no part of the claimed design.
